UNITED STATES PATENT OFFICE.

HERMAN W. OSTER AND WILLIAM J. MACAK, OF CLEVELAND, OHIO, ASSIGNEES TO
THE OSTER MANUFACTURING COMPANY, OF CLEVELAND, OHIO, A CORPORATION
OF OHIO.

DIE-STOCK.

1,116,838.

Specification of Letters Patent. Patented Nov. 10, 1914.

Application filed April 22, 1912. Serial No. 892,289.

To all whom it may concern:

Be it known that we, HERMAN W. OSTER and WILLIAM J. MACAK, citizens of the United States, and residents of Cleveland, in the county of Cuyahoga and State of Ohio, have invented a certain new and useful Improvement in Die-Stocks, of which the following is a full, clear, and exact description.

10 The object of this invention is to provide a cheap and efficient die stock wherein the dies will gradually recede as the thread is being cut, whereby they will cut what is known as tapered threads.

15 The invention consists in the construction and combination of parts hereinafter described and pointed out definitely in the claims and shown in the accompanying drawings wherein—

20 Figure 1 is a central longitudinal sectional view, and Fig. 2 is a front end view with certain parts broken away.

The work holder 1 is of familiar construction, being a built up member of tubular form, so that the pipe or cylindrical piece of work to be threaded may be passed through it, and being provided with suitable means whereby it may be clamped to the work. The die carrier 2 is likewise tubular, and is capable of being moved rotatably and longitudinally relative to the work holder. In the construction shown the die carrier has its rear end externally threaded so that it may be screwed into the internally threaded work holder; wherefore as the die carrier is turned relatively to the work holder it will move longitudinally relative thereto at such a rate as is determined by the pitch of the engaging screw threads.

25 At the front end of the die carrier is an outwardly extended flange 2^a which is provided with a plurality of pairs of forwardly projecting lugs 2^b, 2^c, which serve as guideways to determine the path of movement of the die cases 4 which lie between them. These die cases have ribs 4^a on their sides which go into the grooves in the inner faces of these lugs. The dies 3 are fitted into these die cases. The rear end of each abuts

30 a shoulder 4^b on the associated die case, and it is held down by gibbs 4^c which are fixed to the top edges of the die case, so as to overhang and engage with the die therein.

35 represents a ring which is rotatively mounted on the work holder, but is held

against longitudinal movement,—the particular means shown for accomplishing this result being an annular groove 1^a in the work holder, and one or more pins 5^a which screw through the ring and project into this groove. This ring has outwardly projecting lugs 5^b, which lugs may be parts of a continuous flange, if desired. Through each of these lugs a hole 5^c is formed; and through each of these holes passes a lever 6. The rear end of this lever is pivoted to inwardly projecting ears 2^d formed on the rear end of an arm 2^e which is fixed to the flange 2^a of the die carrier, and is extended rearward therefrom outside of and past said ring. These so-called arms are parts of a cylindrical flange,—but the parts of the flange between the so-called arms have no other function than to furnish a housing over the ring and levers. Each lever 6 from its pivot to its front end extends through the hole 5^c and at a slight angle toward the axis of the tool. Its upper end passes through a slot 2^f in the flange 2^a and enters a recess 4^d in the rear face of the associate die case. This recess and end of the lever are curved so that they will fairly well fit each other under all conditions. Moreover, the inner and outer margins of the holes 5^c are so shaped that the lever will have an operative engagement with them under all conditions. When, now, the die carrier is screwed into the work holder, the lever 6 will, of necessity, since it passes through the hole 5^c, be caused to assume a position more and more nearly parallel with the axis of the tool. This will compel an outward movement of the die case and die carried thereby, or it will control such outward movement when produced by the out-thrust of the work upon the dies. In other words, the die cases and dies will gradually recede as a thread is being cut upon a pipe properly held in the work holder so that the thread so cut will be what is known as a tapered thread.

Having described our invention, what we claim is:—

1. In a die stock, the combination of a work holder, a die carrier which is rotatable and movable longitudinally relative to the work holder, radially movable dies carried by the die carrier, a ring which is rotatably mounted on the work holder but is held against longitudinal movement there-

on, which ring has longitudinal holes extended through it, arms fixed to the die carrier and extending rearward outside of and past the ring, and levers pivoted to said arms and extended through the holes in the ring, and means transmitting motion of the front ends of said levers to said dies.

2. In a die stock, the combination of a work holder, a die carrier which is rotatable and movable longitudinally relative to the work holder, radially movable dies carried by the die carrier, a ring which is rotatably mounted on the work holder but is held against longitudinal movement thereon, which ring has longitudinal holes extended through it, arms fixed to the die carrier and extending rearward outside of and past the ring, die cases which are radially movable on the die carrier and in which the dies are fixedly held, said cases having in their rear faces curved recesses which receive respectively the front ends of said levers.

3. In a thread cutting device, a stock body adapted to carry a die, a leader bushing screwing upon said body and adapted to be fastened to the work, a rotatable laterally fixed ring, and a lever operatively engaging said die and being controlled jointly by said ring and stock body, said lever being oblique to the axis of the stock body and being pivoted to one of the two last mentioned parts and always engaging the other of said parts at a point having a fixed distance from the axis of rotation and a fixed position lengthwise of the axis of rotation. 25 30 35

In testimony whereof, we hereunto affix our signatures in the presence of two witnesses.

HERMAN W. OSTER.
WILLIAM J. MACAK.
